United States Patent Office

Des. 185,100
Patented May 5, 1959

185,100

TONGUE DEPRESSOR

Raphael Schlosser, Portland, Oreg.

Application November 15, 1957, Serial No. 48,481

Term of patent 14 years

(Cl. D83—12)

FIG. 1

FIG. 2

FIG. 3

FIG. 4

FIG. 5

FIG. 6

Figure 1 is a top plan view of a tongue depressor, showing my new design;

Figure 2 is a side elevation thereof;

Figure 3 is a bottom plan view thereof;

Figure 4 is a longitudinal sectional view taken along the line 4—4 in Figure 3;

Figure 5 is an end elevation thereof as viewed from the left in Fig. 2; and

Fig. 6 is an end elevation thereof as viewed from the right in Fig. 2.

I claim:

The ornamental design for a tongue depressor, as shown.
